DESIGN FOR A HINGE

Janet P. Carruthers, Freeport, Ill., assignor to Arcade Manufacturing Company, Freeport, Ill.,
a corporation of Illinois

Application June 12, 1937, Serial No. 69,818

Term of patent 7 years

To all whom it may concern:

Be it known that I, Janet P. Carruthers, a citizen of the United States of America, residing at Freeport, in the county of Stephenson and State of Illinois, have invented a new, original, and ornamental Design for a Hinge, of which the following is a specification, reference being had to the accompanying drawing, forming a part thereof, in which:

Fig. 1 of the drawing is a face view of a hinge, showing my new design; Fig. 2 is an edge view of the hinge; and Fig. 3 is a sectional view taken at the line 3 on Fig. 1 and viewed in the direction of the arrow.

I claim:

The ornamental design for a hinge, as shown.

JANET P. CARRUTHERS.
